SHEET REGISTERING MECHANISM

Leonard H. Cross, Nassau County, N. Y.

Application August 14, 1940, Serial No. 352,511

12 Claims. (Cl. 271—46)

My invention relates to sheet-registering mechanism used in conjunction with sheet-feeding and delivery means for bringing sheets in individual sequence to the cylinder of a printing press. More particularly, the invention relates to such registering mechanism which employs pull-grippers adapted to positively grip the sheet and positively advance it for engagement with stationary drop-guides forming part of such registering mechanism, said grippers being adapted to frictionally draw away from the sheet after such engagement. This type of mechanism is clearly distinguished from mechanism adapted to impositively engage and push the sheet into engagement with the drop-guides and adapted to also push upon the sheet during the registry period following its initial engagement with the drop-guides.

An important aspect of my invention is the provision of means cooperative with the pull-grippers to slow down the sheet prior to its engagement with the drop-guides of the registering means and the provision of means causing continual advancement of the sheet under positive control during said operations.

Some prior mechanisms continually push the sheet during the slow-down as well as during the registering period of its advancement. This causes buckling which mitigates accurate registry and causes scuffing of the surface of the sheet. Other prior machines impositively retard the sheet in the slow-down period. This also causes buckling, and further, permits the sheet to rebound, tending to crimp the front edge and otherwise destroy accuracy of registry. Still other prior devices require that the sheet be brought to rest prior to engagement of registering grippers, causing a reduction in efficiency.

Some of these prior mechanisms have their slow-down means combined with their means for delivering and transferring the sheet to relatively stationary jaws of independent pull-grippers. This type suffers inaccuracy on account of the wide variation in arrival of the sheets to an anticipated point between the said jaws at the time of transfer of control of the sheet from the delivery means to the registering means. This variation in arrival of the sheets is due to a number and variety of causes well understood in the art. In such mechanisms, sheets arriving on schedule are not free of buckling and impact which are inherently associated with impositive control and transfer.

Impacts also occur during transfer of feed control from one set of positively gripping feed

means to another set of positively gripping feed means operating at a wide difference of advancing speeds.

Other objections of the prior device are their inability to take care of a relatively wide range of variations between sheets far ahead or far behind their normally anticipated arrival on schedule.

One of the main objectives of my invention is to overcome the objections to prior devices adapted for registering of sheets and to increase the range of acceptance for registry, of oncoming sheets which are far ahead or behind schedule. Another object is to provide a highly efficient device which supplements the pull-grippers with slow-down characteristics for engagement with front edge of a controlled advancing sheet for controlled retardment to registry mechanism to secure uniformly accurate front edge registry. Other Objectives are to provide means in my contemplated mechanism for engaging a sheet while traveling at high speed without causing impact or inertia reactions in the sheet, and thereafter, to effectuate a gradual deceleration thereof, prior to registry, to a speed where it is brought into contact with the stationary drop-guides for registry, without impact or rebound. A further object is to provide an equal period of slow-down action on all sheets regardless of their schedule of arrival within the wide limits of the mechanism.

Other objects and advantages are contemplated, some will be specifically pointed out and yet others will become apparent in the following specification having reference to the accompanying drawings showing preferred embodiments of my invention, in which:

Fig. 1 is a fragmentary semi-schematic sectional view of the forward end of a conventional sheet conveying mechanism of the type known in the art as a "cross feeder," embodying the invention, with the parts thereof in an initial operating position at the beginning of the forward stroke in the cycle of operation.

Fig. 2 is a fragmentary view similar to Fig. 1 showing certain parts in an advanced operating position.

Fig. 3 is a view similar to Fig. 2 showing the parts in a still further advanced operating position.

Fig. 4 is a view similar to Fig. 3 showing the parts in an operating position at the completion of the forward stroke.

Fig. 5 is a fragmentary section taken substantially on the line 5—5 of Fig. 1.

Fig. 6 is a view taken substantially on the line 6—6 of Fig. 2.

Fig. 7 is a fragmentary view of a modified form of gripper in the position at the beginning of the registry of an early sheet.

Fig. 8 is a sectional view taken on the line 8—8 of Fig. 7.

Referring to Fig. 1 a conveyor mechanism comprising feed-board 10 is suitably supported by the machine in any well known manner, not shown, so that its forward end overlies a cylinder 12 of a printing press. Conveyor strips 14 are supported on the feed board, the forward edge tapering off. A pair of frame members 16 are adapted to provide bearings 18 for a rock shaft 20. One of said frames is positioned on each side of the conveyor strips and supported upon the feed board. Bearings 22 on these end frames are provided to rotatably support a cam shaft 24 on which is carried a cam 26 having cam surfaces A, B, and C, comprising respectively an accelerating, decelerating, and substantially constant slow speed zones of the operation of the registry gripper jaws to be later described. These zones relate to the effect these cam surfaces have upon the motion of the sheet gripping jaws in their forward stroke.

Secured to the shaft 20 is a rocker arm 28 having a follower 30 urged against the cam 26 by spring 27. Also secured to the rock shaft 20 is an arm 32 connected by link 34 to an extension 35 of an arm 36. Two of such arms 36 are employed, only one being shown and these are pivotally supported as at 38 in extensions 40 secured to stationary arms 42. Only one of this described assembly is shown and described in detail. This arm 42 is adjustably secured to the frame 16 by means of a pin 44 and a pin-and-slot arrangement 50 and 52. This arm is fixedly adjustable by means of set screws 48 in the pin 50 cooperable within the slot 52 embracing the pin and the screws.

Pivoted as at 56 is extensible arm 58 having a laterally projecting pin 60 at its forward end. This arm is provided with a pin and slot adjustment 62 to enable it to be lengthened or shortened for the purpose to be more fully described later. The arm 58 is pivotally secured as at 56 to a boss 54. A pin 60 at the free end of this arm is adapted to rest upon the upper edge of a blade 64. This blade is pivotally secured as at 66 to the free end of the arm 36 and is adapted to shuttle back and forth as motivated in response to the surfaces A, B, and C, etc., of the cam 26. Pivotally secured as at 68 to the shuttle blade 64 is a blade 70 having a hook 72 adapted to rest on the pin 60, the said hook forming a rearwardly open slot 74 adapted to permit the blade 70 to become disengaged from the pin 60 so that its finger 78 can engage a sheet of paper S under it. The sheet is thus clamped between the jaw 76 and under a jaw 78 secured at its forward end to the shuttle blade 64. The free end of this under jaw 78 is rearwardly directed. In raised position of the blade 70 the jaws 76 and 78 form a mouth for the reception of the forward edge of an oncoming sheet.

The tip 80 of the shuttle blade 64 is widened laterally and its bottom surface is curved fore and aft as at 82 so that it is well adapted to rest and ride along the upper surface of a tongue 84 extending forwardly from under the feed board 10 projecting over the upper surface of the cylinder, and terminating under and slightly forward of the drop-guides 86. The drop-guides may be

of such conventional type as are supported in a rocker arm 88, and adapted to be raised and lowered in phased relationship with the cam 26, all of which motions are cyclically timed to the operation of the cylinder. The drop-guides 86 may be provided with the usual slot to form a fork through which the tip 80 and the jaws 76 and 78 may pass.

Projecting forward from the upper surface of the feed board 10, and underlying each of the blade assemblies is a channeled strip 90, see fig. 5, having a groove or recess 92 therein, of such width as to receive the end of the shuttle blade 64 including its jaw 78. The depth of said recess 92 is preferably such as to receive the projecting end of the jaw 78 completely below the surfaces 94 to prevent its interfering with the front edge of an oncoming sheet.

Rotatably secured to the extension arm 40 is a pin 100 through which a rod 102 is adapted to slide. The lower end of this rod is pivotally secured as at 104 to the shuttle blade 64. The upper end is threaded to receive lock nuts 106. The purpose of this will be more fully described later.

Referring to Fig. 1, it is to be observed that upon rotation of the cam 26 in the direction shown by the arrow, the arms 32 and 35 will be swung clockwise, thus bringing the blades forward as illustrated in Fig. 2. During the rotation of the cam under the effect of its surface A, the blades 64 and 70 are rapidly accelerated from their rearmost position. At the end of the effect of the zone A of the cam, the instant which corresponds to advancement of the pivot pin 66 to the point E, the arm 36 has reached its maximum rotative speed and, coincidentally, the maximum speed of the forward motion of the blades. At this time the hook 72 becomes disengaged from the pin 60 permitting the jaw 78 to come into contact with the sheet, which, under normal operation and schedule, is positioned with its forward edge substantially midway between the contactable surfaces of the fingers 76 and 78. From this point on and during actuation of the zone B of the cam, the blades are decelerated to a point where the pivot 66 reaches the position F, a position shown in Fig. 3. This period of deceleration is relatively long as compared to impact devices. This substantially long period of deceleration prevents buckling of the sheet due to gradual reduction of the momentum of the sheet. From this point on the sheet is advanced at a substantially constant and low speed, much lower than the speed at which the sheet was initially fed to the gripping fingers or the speed at which the sheet is clamped between the fingers.

It will be observed in Fig. 3 that at the time the blades have completed their deceleration, the front edges of the gripping surfaces of the jaws have reached the rear face of the drop-guides 86 and are ready for sheet registry, even for an early sheet if such happens to be the case. As will be seen, the front edges of the sheet, under more normal schedule conditions, is arranged to be no further forward than the middle of the gripping surfaces of the jaws. Under conditions of receiving a tardy sheet however, little of the front edge of the sheet will be grasped by the gripping jaws by the rear portions of their gripping surfaces. In an actual embodiment of the character illustrated, I have found that this mechanism is conveniently operable with a stroke of a little over three inches of the blades, employing about one inch of said stroke.

for acceleration, one half an inch for deceleration, leaving one and one half inches for the registering motion of the blades. This last portion of the forward stroke provides ample motion at slow speed for the accurate registration of sheets which are as much as three quarters of an inch early or three quarters of an inch tardy in their arrival between the jaws at the instant of their closing. This is considered a relatively long range of operability on mistimed sheets.

During the last portion of the forward stroke when the follower 30 is operating along the surfaces C of the cam and the blades are moving between the points F and G at a substantially constant slow speed, the jaws are in frictional engagement with the sheet and are continually moving forward during withdrawal from the sheet upon registry and no rebound occurs. The last portion of the forward motion of the blades is changed by the engagement of the nut 106 with the pin 108, thereby causing the forward end of the blades to rise, but only after the trailing end of the jaw 78 has passed the indexing face of the drop-guides 86 with which the sheet came into contact. This final lift of the tip of the blades consumes very little of the final forward motion. In the raised position of the blades as illustrated in Fig. 4, the sheet is seized by the cylinder grippers and, as is well known, 30 carried into the press.

It will be further noted that as the tip 80 of the blade 64 advances to the left, the angle of the blade 64 becomes more horizontal, thereby causing the rearmost portion of the spring finger 78 to recede further down into the recess 92, and it is obvious therefore, that in the highest position of the tail end of the finger 78 it is below the lower most surface of an oncoming sheet, that a tardy oncoming sheet cannot be 40 intercepted by the trailedge of the fingers 78. It will also be seen that in order to accurately adjust the point at which the contacting finger of the blades cooperate to grip the sheets, the pin 60 may be adjustably positioned in the direction of movement of the blades by means of the pin-and-slot connection 62. The pin 60 however, is free to follow the vertical variations of the arcuation of the blade 64 inasmuch as the arm 58 is freely pivoted at 56. In other words, 50 the two blades are held apart during their forward accelerating motion regardless of minor vertical articulation inasmuch as the pin 60 supports the hook blade and is in turn supported on the upper edge of the other blade, the dips of which it can freely follow.

Under certain conditions of operation with certain types of sheets, the sheet-engaging surfaces need not be kept apart until after the entry of the sheet between them, such sheets may be pushed between yieldably opposing frictional surfaces.

Referring to Figs. 7 and 8, it will be seen that such sheet-gripping surfaces of the sheet retarding and pulling means may be provided by the under surface 78a of a reciprocatory blade 64a and an opposing upper surface 78a of a spring arm 78b normally urged toward the surface 78a for frictional engagement of the sheet pushed between these surfaces by the sheet delivery 70 means not shown. This occurs during the initial fraction of the forward stroke of the blade. After this period of engagement of the sheet between the gripping surfaces, the continued forward motion of the blade 64a is retarded, thus 75

slowing down the sheet. The said engagement of the sheet and the subsequent slowing down all occur within substantially the same cam zones A and B and cyclic relationships as previously described.

Following the slow-down period, the sheet S is slowly advanced until its edge comes into engagement with first one and then the other of the two relatively stationary drop-guides, whereafter, the sheet-engaging surfaces are slowly withdrawn from the engagement therewith by their continued forward movement after the sheet has been arrested in registry by the drop-guides. The pressure of the frictional sheet-engaging surfaces may be adjusted by means of the screws 78c so that any momentum of the sheet is overcome after the feeding influence of the delivery mechanism ceases. Such adjustment permits entry of the sheet between the surfaces of the grippers without buckling. After such engagement, the front edge of the sheet is brought into contact with the drop-guides. This pressure is relatively slight so as not to crimp the sheet in its withdrawal from the grippers during registry. In this modification as well as in the former, the portion of the registering edge which engages the drop-guides is protected against crimping by being confined and reinforced by the said frictional surfaces.

Having thus described my invention in its principal aspects with reference to the specific embodiments thereof, it is understood that similar organizations and arrangements are adapted to other types of machines involving merely such changes as to enable adaptation of the principles of this invention to the particulars of such machines. Other variations may be made without departing from the spirit of the invention as defined in the claims appended.

I claim:

1. In sheet registering mechanism of the character described, the combination including means for positively advancing a sheet forward for a predetermined period, reciprocatory jaws disposed on opposite sides of the path of said advancing sheet, gripping surfaces on said jaws adapted to engage the forward portion of said sheet on opposite sides thereof, means on one of said jaws for urging said surfaces into frictional engagement with said sheet on respective sides thereof, means for advancing said jaws forwardly in open position with one jaw on either side of said advancing sheet and for engagement thereof while in motion without retarding the speed of the sheet at the instant of engagement, and means for retarding the motion of said jaws after said engagement of the sheet by said gripping surfaces.

2. In sheet registering mechanism of the character described, the combination including means for positively advancing a sheet forward for a predetermined period, reciprocatory jaws disposed on opposite sides of the path of said advancing sheet, gripping surfaces on said jaws adapted to engage the forward portion of said sheet on opposite sides thereof, means on one of said jaws for urging said surfaces into frictional engagement with said sheet on respective sides thereof, means to accelerate said jaws not faster than the speed of the sheet in the initial fraction of their forward stroke into cooperative relationship with said advancing sheet for engagement thereof while in motion, and means for decelerating said jaws in a succeeding fraction of said forward motion of said jaws.

3. In sheet registering mechanism of the char-

acter described, the combination including means for positively advancing a sheet forward for a predetermined period, reciprocatory jaws disposed on opposite sides of the path of said advancing sheet, gripping surfaces on said jaws adapted to engage the forward portion of said sheet on opposite sides thereof, means on one of said jaws for urging said surfaces into frictional engagement with said sheet on respective sides thereof, means to accelerate said jaws not faster than the speed of the sheet in the initial fraction of their forward stroke into cooperative relationship with said advancing sheet for engagement thereof while in motion, and means to retard said jaws in a succeeding fraction of their forward stroke and after said engagement of the sheet.

4. In sheet registering mechanism of the character described, the combination including means for positively advancing a sheet forward for a predetermined period, reciprocatory jaws disposed on opposite sides of the path of said advancing sheet, gripping surfaces on said jaws adapted to engage the forward portion of said sheet on opposite sides thereof, means on one of said jaws for urging said surfaces into frictional engagement with said sheet on respective sides thereof, and means prescribing the forward motion of said jaws to comprise an initial accelerating fraction for bringing said jaws into cooperative relationship with said advancing sheet for engagement therewith; an intermediate decelerating fraction after said engagement, and a final relatively slow constant speed motion adapted for registry and disengagement of the jaws from said sheet.

5. In a sheet registering mechanism of the character described, the combination of means adapted for reciprocatory motion in unison with moving successive sheets, the forward stroke being in the same direction as the direction of travel of the sheets, said forward stroke including an initial accelerating fraction, means prescribing said fractions in timed relation to the leading portion of each oncoming sheet, opposing surface on said reciprocatory means adapted to engage the forward portion of a passing sheet on opposite faces thereof, means yieldably urging said surfaces into engagement, means for holding said surfaces apart during the accelerating fraction of said stroke, means for decelerating the forward motion of said reciprocatory means, and means for disabling said holding means at a predetermined period at the end of said accelerating fraction of the forward stroke.

6. In a sheet registering mechanism of the character described, the combination of means adapted for reciprocatory motion in unison with moving successive sheets, the forward stroke being in the same direction as the direction of travel of the sheets, said forward stroke including an initial accelerating fraction, means prescribing said motions of said fractions in timed relation to the leading portion of each oncoming sheet, opposing surfaces on said reciprocatory means adapted to engage the forward portion of a passing sheet on opposite faces thereof, means yieldably urging said surfaces into engagement, means for holding said surfaces apart during the accelerating fraction of said motion, means for decelerating the forward stroke of said reciprocatory means, and means for disabling said holding means at a predetermined instant in its forward stroke, said instant being related to the speed of the travel of the sheet.

7. In a sheet registering mechanism of the character described, the combination of means

adapted for reciprocating motion in unison with moving successive sheets, the forward strokes thereof being in the direction of travel of the sheets, opposing surfaces on said means adapted to frictionally engage opposite sides of the leading portion of each oncoming sheet, means yieldably urging said surfaces into engagement with said sheet, means for holding said surfaces apart during a predetermined fraction of the forward motion of said reciprocatory means, and means allowing the said surfaces to move toward engagement of a sheet in motion during another predetermined fraction of their forward motion and for engaging said sheet when the speed of said surfaces is substantially equal to the speed of the moving sheet.

8. In a sheet registering mechanism of the character described, the combination of means adapted for reciprocating motion in unison with moving successive sheets, the forward strokes thereof being in the direction of travel of the sheets, opposing surfaces on said means adapted to frictionally engage opposite sides of the leading portion of an oncoming sheet while in motion, means yieldably urging said surfaces into engagement, and means for holding said surfaces apart during an initial fraction of said forward stroke of said reciprocatory means, and allowing said surfaces to engage a sheet in motion during a succeeding instant of their forward stroke without retarding the speed of the sheet at the said instant of engagement.

9. In a sheet registering mechanism of the character described, the combination of means adapted for reciprocating motion in unison with moving successive sheets, the forward strokes thereof being in the direction of travel of the sheets, opposing surfaces on said means adapted to frictionally engage on opposite sides the leading portion of a moving sheet, means yieldably urging said surfaces into engagement with said sheet during its travel, means for holding said surfaces apart during an initial fraction of said forward stroke of said reciprocatory means, and means disabling said holding means during the remaining fraction of the said forward stroke of said reciprocatory means for engagement with said sheet at an instant when the speed of the said surfaces is equal to the speed of said moving sheet.

10. In a sheet registering mechanism of the character described, the combination of means adapted for reciprocation motion in unison with moving successive sheets, the forward strokes thereof being in the direction of travel of the sheets, opposing surfaces on said means adapted to move in unison and frictionally engage opposite sides of the forward portion of an oncoming sheet, means yieldably urging said surfaces into engagement during said forward stroke, means for holding said surfaces apart during the initial fraction of the forward stroke of said reciprocatory means, means for accelerating the motion of said opposing surfaces during said initial fraction, means for decelerating the motion of said reciprocatory means during a succeeding fraction of said forward stroke, and means disabling said holding means during the motion of said reciprocatory means in a period between said accelerating and decelerating fractions of the forward stroke.

11. In a sheet registering mechanism of the character described, the combination of means adapted for reciprocatory motion in unison with moving successive sheets, the forward stroke be-

ing in the same direction as the direction of travel of the sheets, said forward stroke including an initial accelerating fraction, means prescribing said motions in timed relation to the leading portion of each oncoming sheet, opposing surfaces on said reciprocatory means adapted to engage the forward portion of an oncoming sheet on opposite faces thereof, means yieldably urging said surfaces into engagement while moving, means for holding said surfaces apart during the accelerating fraction of said motion, means for decelerating the forward stroke of said reciprocatory means, and means for disabling said holding means at a predetermined instant in its forward stroke, said instant being when the speed of the surfaces is substantially the speed of travel of the sheet.

- 10
- 15
- 5
12. In a sheet registering mechanism of the character described, the combination including reciprocatory means acceleratable in the initial portion of its forward stroke and adapted to move in unison with each successively moving sheet, opposing surfaces on said reciprocatory means adapted to engage on opposite sides of the leading portion of each of successively moving sheets, yieldable means on said reciprocatory means urging said surfaces into said engagement with each moving sheet, and means for holding said surface from said engagement during a predetermined fraction of said forward stroke.

LEONARD H. CROSS.
